UNITED STATES PATENT OFFICE.

ALLAN SCOTT WOLFE, OF WASHINGTON, DISTRICT OF COLUMBIA.

COMPOSITION FOR CLEANSING ARTIFICIAL DENTURES AND THE LIKE.

1,345,819.

Specification of Letters Patent.

Patented July 6, 1920.

No Drawing.

Application filed October 1, 1919. Serial No. 327,811.

To all whom it may concern:

Be it known that I, ALLAN SCOTT WOLFE, a citizen of the United States, residing at Washington, in the District of Columbia, 5 have invented certain new and useful Improvements in Composition for Cleansing Artificial Dentures and the like, of which the following is a specification.

The invention relates to a composition 10 of matter intended more particularly for cleansing artificial dentures, surgical appliances and the like, and the process of its application; the terms "artificial dentures" and "surgical appliances" are intended to 15 cover all devices worn removably in the oral cavity, such as dental plates, orthodontia plates, fracture splints, and obturators for cleft palates, whether of metal, vulcanite or other material.

20 It is known that when dental plates or other dental or surgical appliances are worn in the mouth for any considerable period of time mucous and other foreign matter will adhere thereto, forming a thick, 25 tough, slimy coating, thus creating unsanitary and extremely disagreeable conditions. The only method of removing this coating hitherto has been that generally employed in the dental laboratory, consisting in the 30 use of stiff brushes or felt cones with an abrasive on a lathe, necessitating the refinishing and re-polishing of the denture. The term "mucous" herein is that ordinarily used by dental practitioners and is intended to 35 designate the mucin-containing secretions of the oral glands and the difficultly removable residues thereof adhering to the artificial denture or the like.

The compound forming the subject of the 40 present invention is a preparation by means of which the person wearing the denture or appliance is enabled to cleanse it rapidly and thoroughly and without injury to the polished surface thereof by simply rubbing it on the artificial plate or the like with a brush, a cloth or with the fingers, and then washing it off with water.

The cleansing compound comprises a mucous solvent, preferably an acid, for example 45 hydrochloric acid, and a filler, for ex-

ample, powdered asbestos. If desired, a suitable flavoring material, for example, oil of wintergreen, and a suitable coloring matter may be added. Generally, the use of an abradant is to be avoided, but should such 55 be considered necessary a suitable abrasive material, for example, powdered pumice stone, may be incorporated in the mixture.

If the cleansing compound is to be used in the form of a paste—which is the preferred form—a sufficient quantity of a vehicle having the consistency of oil and preferably soluble in water, for example, glycerin, is admixed therewith. The paste may be applied directly to the article to be 60 cleansed and afterward washed off with water.

Any proportion of the acid mucous solvent, for example hydrochloric acid, may be used, it being only necessary to observe 70 care that it be not sufficiently strong to injure the hands in applying the composition containing it to the article to be cleansed.

The following is an exemplary formula 75 of my cleansing composition, the proportions of which can be varied within wide limits:

Hydrochloric acid (5% solution)	8 ounces.
Powdered asbestos	16 ounces.
Glycerin	8 ounces.

80

The acid mucous solvent is incorporated with the powdered asbestos and a quantity of glycerin sufficient to form a paste of the desired consistency is added thereto, and the paste supplied to the consumer in suitable containers, for example, collapsible metal tubes.

I claim:

1. A pasty mass for cleansing artificial dentures and the like consisting of an inert 90 filler impregnated with a mucous solvent in quantity sufficient to remove the mucous from the denture, the mixture being suspended in a viscous vehicle, the cleansing mass being readily removable from the denture by washing in water without leaving residue.

2. A cleansing composition for artificial dentures and the like comprising hydrochloric acid, an inert filler capable of ab- 100

sorbing the hydrochloric acid, and a viscous water-soluble vehicle holding said acid impregnated filler in suspension.

3. A cleansing composition for artificial dentures and the like comprising hydrochloric acid in quantity sufficient to dissolve the adhering mucous residue from the denture, powdered asbestos and glycerin.

4. A cleansing composition for artificial dentures and the like comprising substantially one part of hydrochloric acid, one part of glycerin and two parts of powdered asbestos.

In testimony whereof I affix my signature.

ALLAN SCOTT WOLFE.
